Inventor:

UNITED STATES PATENT OFFICE.

WILLIAM P. RICHARDS, OF UNION CITY, TENNESSEE.

DESIGN FOR A SURGICAL RUBBER PAD.

SPECIFICATION forming part of Design No. 35,749, dated February 18, 1902.

Application filed July 22, 1901. Serial No. 69,338. Term of patent 14 years.

To all whom it may concern:

Be it known that I, WILLIAM P. RICHARDS, a citizen of the United States, residing at Union City, in the county of Obion and State of Tennessee, have invented and produced a new and original Design for Surgical Rubber Pads, of which the following is a specification, reference being had to the accompanying drawings, forming a part thereof.

Figure 1 is a plan view of my design. Fig. 2 is a side elevation of the same, and Fig. 3 is a cross-section.

As shown in the accompanying drawings, the leading or essential feature of my design consists of a circular base 2, having at its outer edge an upwardly-extending ring 1, on the outer face of which is a button 1^a. Said ring

upon its inner and outer faces has circumferential ribs 4, from which extend horizontally flanges 4^a. Transversely to and intersecting the aforesaid ribs are ribs 5. A tube 2^b projects diagonally downward from the base 2, and at the juncture of the base and ring is a bead 3.

Having thus fully described my design, what I claim as new, and desire to secure by Letters Patent, is—

The design for a surgical rubber pad as herein shown and described.

WILLIAM P. RICHARDS.
